United States Patent Office

Des. 184,900
Patented Apr. 14, 1959

184,900

RECORD HOLDER

Richard E. Von Meyer, Sidney, Ohio

Application April 15, 1957, Serial No. 45,743

Term of patent 7 years

(Cl. D33—3)

I claim:

The ornamental design for a record holder, substantially as shown.
